UNITED STATES PATENT OFFICE.

HERBERT R. BLISS, OF NIAGARA FALLS, NEW YORK.

SHIPPING CASE.

Application filed December 6, 1922. Serial No. 605,301.

To all whom it may concern:

Be it known that I, HERBERT R. BLISS, a citizen of the United States, residing at Niagara Falls, in the county of Niagara and 5 State of New York, have invented certain new and useful Improvements in Shipping Cases, of which the following is a specification.

This invention relates to a method of 10 sealing fibre shipping cases by wire-stitching or metallic fasteners. It is the object of the present invention to provide a method by which these shipping cases can be expeditiously and securely sealed.

15 In the drawings:

Fig. 1 is a perspective of the complete sealed case.

Fig. 2 is a perspective of the same before it is packed.

20 Fig. 3 is a diagrammatic view showing how it is sealed.

Fig. 4 is a section taken on the line 4—4 of Fig. 3.

25 Fig. 5 is a perspective of a modified form of shipping case.

Figs. 6 to 8 inclusive show the blanks used to build the case.

From an inspection of the blanks and the perspective view of the case it will be seen

30 that the entire case body and closure, is made from three separate blanks. The end blanks are designated *a* and *b* and are provided with cover wings *a'* and *b'*. The body blank is secured to form the sides *c* *c*, the 35 bottom *d* and the cover wings *e* and *e'*. In the form of construction shown in Figs. 1 and 2, the fastening strips *f* are integral right angularly folded portions of the end blanks. In the form shown in Fig. 5 they

40 are integral right angularly formed portions of the main body blank and are designated *f'*. These forms of construction have great advantages in economy of material and strength of the box at the corners.

45 Now referring to Fig. 3, the closure and the way the fasteners are driven will be understood. A blade anvil such as shown in this figure is used to clinch the fasteners. The first position of the anvil is designated

50 1; the second position is designated 2 and the third position is designated 3. The stitches are numbered in the order they are taken and each anvil position is printed with the numbers of the stitches taken while 55 inserted in the way shown.

The cover wings *e* *e'* preferably just meet

while the underlying cover wings *a'* and *b'* do not quite meet at the center but may be somewhat spaced. The underlying cover wings *a'* and *b'* are first folded in; the cover wing *e* is then folded over while the cover wing *e'* is folded back out of the way. Now, obviously the anvil in position No. 1 is free to be inserted in the open space between the edges of the underlying cover wings *a'* and *b'*. Stitches 1, 2, 3, 4, 5, 6, 7 and 8 may be taken, or any different number of stitches and the order may be varied. The anvil is in the same position so far as its means of access to the under-side of the part but of course the box has to be swung around on the anvil to take the various stitches. Next the cover wing *e'* is folded down on top of the underlying cover wings and the anvil is inserted under the cover wing *e'* and over the cover wing *b'* as shown in position 2 Fig. 3. This permits stitches 9, 10 and 11 to be taken leaving, however, an opening between stitch 11 and the side of the case big enough to insert the anvil in position 3. In this position the anvil overlies the cover wing *a'* and underlies the cover wing *e'* and *b'*. Stitches 12, 13, 14 and 15 may be taken.

It will be obvious that these stitches do not necessarily have to be taken in the order enumerated for after the three separate positions of the anvil are taken, obviously it is simply a matter of choice and convenience so far as the order they are taken in. I have spoken of the anvil being inserted, of course in actual practice the anvil will ordinarily be stationary and the box swung around on a table to cause the anvil to be inserted in the various positions indicated.

What I claim is:

1. The method of sealing a fibre shipping case provided with two pairs of cover wings at the sealing end, comprising the folding in of two of the opposed cover wings and the folding in of the third cover wing over the said two cover wings, inserting a blade anvil under the cover wings and stitching the overlying cover wing to the other two cover wings along the edges of the overlying cover wing, then the withdrawal of the blade anvil and turning down the remaining cover wing, then inserting the blade anvil at one end of such last mentioned turned down cover wing and stitching the opposite end of such cover wing along its free edges to the underlying cover wing leaving however, a space for the subsequent insertion of the

2
anvil, then withdrawing the anvil and inserting the same in such space at the opposite end of such overlying cover wing and stitching the other end of the cover wing 5 to the other underlying cover wing along the free edges of the overlying cover wing.

2. The method of sealing a fibre shipping case having a pair of abutting cover wings and a pair of cover wings which fall short 10 of abutting, which comprises the folding in of the short cover wings and the folding in of one of the abutting cover wings to overlie the short cover wings, the insertion of a blade anvil in the open space at the 15 center of the top of the case under the thus overlapped cover wings, and the driving of fasteners into such overlapped cover wings, the withdrawal of the anvil, the overlapping

of the remaining abutting cover wing, the insertion of the blade anvil under such remaining abutting cover wing at one end so as to underlie both the overlying cover wing and the short underlying cover wing, at the opposite end, the driving of metallic fasteners through such overlapping cover wings at 25 such end of the overlying cover wing but leaving a space for the insertion of the anvil, the withdrawal of the anvil and the insertion of the anvil through such space at the opposite end, the driving of metallic 30 fasteners through the unfastened end of the overlying cover wing and the underlying cover wing, and the withdrawal of the anvil.

In testimony whereof I affix my signature.

HERBERT R. BLISS.
